AUXILIARY AIR FEEDING DEVICE FOR STOVES

Alexander Levin, Washington, D. C., assignor to the United States of America as represented by the Secretary of the Army

Application September 29, 1952, Serial No. 312,180

4 Claims. (Cl. 126—77)

(Granted under Title 35, U. S. Code (1952), sec. 266)

The invention described herein, if patented, may be manufactured and used by or for the Government for governmental purposes, without the payment to me of any royalty thereon.

My invention relates to an auxiliary air feeding device for stoves.

An important object of the invention is to provide a device in the form of an attachment unit for a coal burning stove, such as a tent stove, in order to introduce additional air into the combustion space in order to more completely burn the volatile combustion products.

A further object is to provide an auxiliary air feeding unit of the above-mentioned character which may be applied to an existing standard type stove without altering the construction of the same.

A further object is to provide a device of the above-mentioned character which is highly simplified and compact in construction and easy to apply to and remove from the stove.

A further important object is to provide a device of the above-mentioned character which will materially reduce smoking of stoves which burn a low grade of bituminous coal, by supplying additional air into the high temperature zone to promote as nearly complete combustion as possible.

Still another object of the invention is to provide a unit of the above-mentioned character which is inexpensive and lightweight.

Other objects and advantages of the invention will be apparent during the course of the following description.

In the accompanying drawings, forming a part of this application, and in which like numerals are employed to designate like parts throughout the same,

Figure 1 is a perspective view of a coal burning stove for tents or the like equipped with the auxiliary air feeding unit embodying the invention,

Figure 2 is an enlarged central vertical section through the stove and unit,

Figure 3 is a horizontal cross section on line 3—3 of Figure 2,

Figure 4 is a similar section on line 4—4 of Figure 2, and,

Figure 5 is a similar section on line 5—5 of Figure 2.

In the drawings, where for the purpose of illustration is shown a preferred embodiment of the invention, the numeral 10 designates generally a coal burning stove comprising upper and lower separable sections 11 and 12. The lower section 12 of the stove is provided with a suitable grate 13, and has a door 14 providing access to an ash pit 15 within the lower section 12 below the grate. The upper stove section 11 rests upon a flange 16 of the lower stove section and includes a top 17 having a removable lid or cover 18 through which fuel and air are introduced into the stove.

Near and inwardly of the side wall of the upper stove section 11, the same is provided with a relatively short upstanding collar or sleeve 19 which normally serves as the adapter or connecting part for a chimney or smoke-

2

stack 20 when the stove is used without the unit embodying my invention.

My unit 21 comprises a spider-like support including a plurality of short radial lugs or pins 22 which are horizontally disposed and adapted to rest upon the top of the collar 19, Figure 2. The pins 22 are preferably four in number, although six or more of the pins may be employed if desired. The pins 22 have their inner ends extending through radial openings formed in an adapter sleeve 23, and permanently rigidly secured thereto by welding or the like. The inner ends of the pin 22 project radially inwardly of the side wall of the adapter sleeve 23 as shown in Figure 2 for a purpose to be described. The outer ends of the pins 22 are preferably rigidly secured to an annular band or centering ring 22' which fits on the upstanding sleeve 19, as shown.

The adapter sleeve 23 includes an upper enlarged sleeve extension 24, integral therewith and being of the same diameter as the collar 19 and adapted to serve like the collar 19 as the connecting part for the chimney 20 which has its lower end telescopically engaging over the sleeve extension 24, as shown.

The unit 21 further comprises an inner downwardly flaring conical duct section or nozzle 25, provided at its upper end with a reduced cylindrical neck 26, integral therewith and provided in its top end with a plurality of L-shaped slots 27, corresponding in number and spacing to the radial pins 22. The cylindrical neck 26 extends through the stove collar 19 and is substantially smaller in diameter than the stove collar so as to provide a substantial annular passage 27' to permit the downward flow of air into the stove. The neck 26 projects slightly above the upper end of the collar 19 and is adapted to fit slidably within the adapter sleeve 23, as shown. When the neck 26 is introduced into the adapter sleeve 23, the upper ends of the L-shaped slots 27 are aligned with the inner ends of the pins 22, and as the neck 26 moves upwardly, the pins will engage the bottoms of the slots 27. The nozzle 25 is now turned a slight amount clockwise, Figure 2, and the inner ends of the pins 22 will enter the horizontal portions of the slots 27 as shown, and releasably lock the nozzle 25 within the adapter sleeve 23 and collar 19. The entire nozzle 25 is now suspended from the top of the collar 19 by means of the spider-like support including the pins 22 and adapter sleeve 23. As shown in Figure 2, the lower flared end of the nozzle 25 is open and spaced near and above the lower end of the upper stove section 11. The nozzle 25 is preferably provided near its lower end with a plurality of circumferentially spaced air inlet openings 28.

The unit 21 further comprises an outer conical wall or hood 29, separate from the inner nozzle 25 and having the same degree of taper as the inner nozzle but being substantially larger in diameter, as shown. The lower open end 30 of the outer hood 29 is spaced somewhat above the lower end of the inner nozzle 25, and preferably terminates at the group of openings 28. The hood 29 is supported by a plurality of substantially radial lugs 31, rigidly secured to the inner nozzle 25 at suitably spaced points, and the upper end of the conical hood 29 contacts the lower end of the stovepipe collar 19 and has the same diameter as this collar so as to provide a continuous downwardly flaring annular passage 32, communicating with the annular passage 27' and leading at the lower end of the hood 29 into the main combustion space of the stove. The hood 29 is not attached to the collar 19 directly but merely bears against the lower end of the same. Neither is the hood 29 permanently secured to the inner nozzle 25, but merely suspended thereon by means of the lugs 31. With this arrangement, when the inner nozzle 25 is turned counterclockwise within the adapter sleeve 23 and lowered, both the inner nozzle 25

and outer hood 29 are readily removable downwardly from the upper stove section 11, and after removal of the unit 21 from the stove, the outer hood 29 is readily removable upwardly from the inner nozzle 25. The spider-type support including the adapter sleeve 23 and radial pins 22 may be readily lifted from the collar 19 after removal downwardly of the unit 21.

As previously mentioned, the purpose of the unit 21 is to introduce secondary air into the high temperature zone where its flow can be brought into intimate contact with the coal volatiles for ignition. The arrangement is designed so that a substantial supply of air can be drawn into the stove through the passage 32 and orifices 28 to provide auxiliary air where it is found that air infiltration through the lid 18 is insufficient to support the required rate of combustion.

In order to prevent the accumulation of any substantial quantity of volatile mixture near the top of the stove, I may form one or more of the uppermost lugs 31 tubular, as at 33, for registration with small openings 33' in the hood 29, near the upper end of the same. This places the interior of the nozzle 25 in communication with the main combustion space near the top of upper stove section 11. With this arrangement, the volatiles which tend to accumulate at the top of the stove will be drawn into the nozzle 25 and ignited by the hot combustion products rising through the nozzle 25. If desired, the openings 33' and the openings of the uppermost lugs 31 may be omitted entirely.

In use, as the bituminous coal on the grate 13 burns, some air enters the stove through the top lid 18 for supporting combustion. The hot combustion products will rise through the tapered inner nozzle 25 and enter the chimney 21, thus creating a strong up-draft and suction. When this occurs, fresh air will be drawn into the top of the collar 19, exteriorly of the neck 26 and downwardly through passages 27' and 32, the top of the collar 19 being entirely open except for the radial pins 22. This downwardly flowing auxiliary air will enter the main combustion space of the stove from the lower end of the passage 32, and some of the inflowing air will enter the lower end of the nozzle 25 by way of the openings 28. This auxiliary air commingles with any unburned combustible products still within the main combustion space and within the nozzle 25, and aids in igniting and inducing substantially complete combustion of the same, thus reducing soot accumulation in the stove and chimney as well as smoking of the stove to a minimum.

It is to be understood that the form of the invention herewith shown and described is to be taken as a preferred example of the same, and that various changes in the shape, size, and arrangement of parts may be resorted to, without departing from the spirit of the invention or scope of the subjoined claims.

I claim:

1. A stove comprising a body portion including a top having an opening, an upstanding collar secured to said top adjacent said opening, a spider support mounted upon the top of the collar over said opening and including substantially horizontal radial elements having their inner ends extending radially inwardly of the margin of said opening, the spider support being adapted for attachment with a chimney extending above said opening, a depending flared nozzle arranged within the body portion and having its upper portion extending into said opening and provided near its upper end with slots receiving the inner ends of the pins for detachably securing the nozzle to the spider support, the lower end of the nozzle extending a substantial distance below the top of the body portion and into the high temperature zone of the stove, the nozzle having a plurality of side openings formed therein near its lower end, spaced radial elements secured to the side wall of the flared nozzle, at least one of the elements having a passage extending therethrough and leading into the flared nozzle near and below the top

of the body portion, and an outer flared hood surrounding the flared nozzle in spaced substantially concentric relation and engaging the radial elements and supported thereby, the top end of the hood substantially contacting the top of the body portion and registering with said opening in the top of the body portion, the lower end of the hood terminating near the side openings of the flared nozzle, the hood being provided near its top end with at least one side opening registering with said passage of the radial element.

2. A stove comprising a body portion including a top having an opening, an upstanding collar secured to said top adjacent the opening, a spider support mounted upon the top of the collar and including substantially horizontal radial elements having inner ends which extend radially inwardly of the side wall of the collar and margin of said opening, an open-ended downwardly flared nozzle disposed within the body portion and separate from the spider support and having an upper end portion extending into said opening and collar and provided near its upper end with upwardly opening bayonet slots receiving the inner ends of the radial elements for detachably securing the nozzle to the spider support, the lower end of said nozzle extending a substantial distance below the top of the body portion and into the high temperature zone of the stove, spaced radial elements secured to the side wall of the nozzle, and an outer open-ended downwardly flared hood surrounding the nozzle in spaced generally concentric relation therewith and resting upon said radial elements and supported entirely thereby, the top end of the hood substantially abutting the underside of the top of said body portion and substantially registering with the opening in the top of the body portion, the top end of the hood terminating short of the top end of said nozzle and a substantial distance below the elevation of the spider support, the lower end of the hood extending near the elevation of the lower end of said nozzle.

3. A stove comprising a body portion including a top, an upstanding tubular extension secured to said top of the body portion and communicating with the interior of the body portion, a spider support resting upon the top of the tubular extension and including a plurality of spaced substantially radial arms having their inner ends projecting inwardly of the side wall of the tubular extension, an open-ended downwardly flared nozzle disposed within the body portion and projecting a substantial distance below the top of the body portion and having an upper end portion extending through said tubular extension in spaced substantially concentric relation therewith, said upper end portion of the nozzle having upwardly opening generally L-shaped slots formed therein to receive the inner ends of said arms for detachably securing the nozzle to the spider support, said arms bodily supporting the nozzle, spaced radial elements secured to the nozzle below the top of the body portion, and an outer open-ended downwardly flared hood surrounding the nozzle in spaced generally concentric relation thereto and resting upon and bodily supported by said radial elements, the top end of said hood substantially registering with said tubular extension and abutting the top of the body portion for providing a substantially continuous annular passage between the nozzle, hood and tubular extension.

4. A stove comprising a body portion having a top, an upstanding tubular extension secured to the top and communicating with the interior of the body portion, a spider support resting upon the top of the tubular extension and including a plurality of spaced radial arms projecting inwardly of the side wall of the tubular extension, a chimney adapter sleeve secured to the spider support and extending above said radial arms and tubular extension for connection with the chimney, a downwardly flared nozzle disposed within the body portion and having an upper end portion extending through the tubular extension in spaced substantially concentric relation thereto, the upper end portion of the nozzle having bayonet slots

for cooperation with said arms so that the arms may support the weight of the nozzle, spaced radial projections formed upon said nozzle below the top of the body portion, and an outer downwardly flared hood surrounding the nozzle in spaced substantially concentric relation thereto and resting upon said projections, the upper end of the hood abutting the underside of the top of the body portion and substantially registering with the bore of said tubular extension.
